Primary Examiner — Robin V Webster*(74) Attorney, Agent, or Firm* — Justin W. McCabe; Dunkiel Saunders Elliott Raubvogel & Hand, PLLC(57) **CLAIM**

The ornamental design for a bottle top with filter, as shown and described.

DESCRIPTION

FIG. 1 is a perspective view of a bottle top with filter according to an embodiment of the present invention; FIGS. 2 to 5 are side elevation views of the bottle top with filter of FIG. 1; FIG. 6 is a top view of the bottle top with filter of FIG. 1; and, FIG. 7 is a bottom view of the bottle top with filter of FIG. 1. The broken line showing in FIG. 6 is included for the purpose of illustrating and forms no part of the claimed design.
